UNITED STATES PATENT OFFICE.

WILLIAM A. HALL AND OTIS ROBINSON, OF AUGUSTA, KANSAS; SAID ROBINSON
ASSIGNOR TO SAID HALL.

DISPLAY CABINET.

1,419,846.

Specification of Letters Patent. Patented June 13, 1922.

Application filed July 12, 1921. Serial No. 484,145.

To all whom it may concern:

Be it known that we, WILLIAM A. HALL and OTIS ROBINSON, citizens of the United States, residing at Augusta, in the county of 5 Butler and State of Kansas; have jointly invented certain new and useful Improvements in a Display Cabinet, of which the following is a specification.

This invention relates to cabinet devices 10 for the display of goods for sale, more particularly curtain shades and curtain shade rollers, and has for one of its objects to simplify and improve the construction and increase the convenience and operativeness of 15 devices of this character.

Another object of the invention is to provide a device of this character having means whereby a plurality of sets of shades of varying qualities and colors may be successively disposed in accessible and visible position.

With these and other objects in view the invention consists in certain novel features of construction as hereinafter shown and described and then specifically pointed out in the claims, and in the drawings illustrative of the preferred embodiment of the invention;—

Figure 1 is a front elevation of the improved device.

Fig. 2 is a plan view in section on the line 2—2 of Fig. 1.

Fig. 3 is a vertical section, enlarged.

Fig. 4 is a section on the line 4—4 of Fig. 35 3, and

Fig. 5 is a detached perspective view of one of the holding plates for the goods supports.

The improved cabinet is formed with a 40 base portion 10, vertical corner members 11, and a housing portion above the corner members and including a floor 12 ends 13 back 14 stationary rear top 15 and inclined front top 18, the latter hingedly united at 19 to the 45 top of the housing. The front of the housing is represented at 16 and is hinged at 17 to the floor 12 and is thus foldable downwardly into the position shown by dotted lines in Fig. 3 to expose the lower interior of 50 the housing, while the raising of the hinged top section 18 will expose the upper interior of the housing.

By this means one entire side of the housing is removable to expose the interior, when 55 required.

Connected at their ends to the end members 13 of the housing are a plurality of bars 20, the outer faces of the bars being segments of a circle, so that the bars coact to form a circular bearing.

Bearing against the inner face of each of the ends 13 of the housing is a disk 21, each disk having a central opening to rotatively engage the bars 20 which thus serve as bearings for the disks.

Attached to the inner face of each of the disks 21 is a plate 22, each plate being formed with a central circular opening 23 as shown in Fig. 5 to also rotatively engage the bars 20.

Each of the plates 22 is formed with a plurality of outwardly opening marginal seats 24 arranged as shown in Fig. 5.

It will be noted that the seats are arranged in series, for illustration five in each series, with the seats of each series directed in parallel and staggered relation, as illustrated in Fig. 3.

The seats of the plate 22 at one side are opposite the seats of the plate at the other side, and are adapted to receive the ends of bars 25 to support the goods to be displayed.

The bars 25 are oblong transversely, as shown, with the side faces of the bars of each series in parallel relation, as shown in Fig. 3.

Formed in the margin of one or both of the disks are small sockets 26, one for each of the series of seats for the goods holding members, and attached to one or both of the ends 13 of the housing is a spring pawl device 27 to yieldably and consecutively engage in the sockets as the disks are rotated. The pawl engages the sockets with sufficient force to hold the disks from accidental displacement, but will yield when sufficient force is applied to rotate the disk.

By this means any one of the series of holding members 25 may be disposed rearwardly of the downwardly opening member 16 of the housing, and the article held thereby accessible and visible, through the open side of the housing.

The improved device is intended more specifically for holding window shades and shade rollers in readily accessible position, when required to be displayed to a customer, while at the same time effectually protected when not required to be displayed.

For the purpose of illustration therefor

the members 25 in Fig. 3 are shown supplied with conventional curtain roller brackets 28 of the usual construction, to receive the curtain rollers, indicated by dotted lines in 5 Fig. 3.

By this arrangement it will be obvious that any desired curtain shade or other article supported on any one of the holding members 25 may be quickly disposed in 10 visible and accessible position by merely rotating the disks 13 against the resistance of the spring pawl 27.

As arranged all of the articles supported on any one series of the holding members 15 may be simultaneously displayed when the member 16 is opened.

It will be obvious that curtain shades or other articles supported by the members 25, one or more, or all of the shades supported 20 by each series of the members 25, may be drawn outwardly over the downwardly opened member 16, as shown by dotted lines in Fig. 3, and thus disposed in position for 25 inspection by a customer, without injury to the shades and with the minimum of effort or labor to the clerk.

One or more drawers 28 will preferably be located above the base 10 and between the closure member 29 of the drawers and the 30 floor 12 of the housing, and a plurality of shelves 30 are located in spaced relation between the floor 12 and the closure member 29.

A plurality of vertical dividing strips 31 are arranged at intervals between the members 12 and 29 in the spaces between the shelves to divide the interior of the cabinet into a plurality of uniformly sized pockets or receptacles as illustrated in Fig. 3.

The ends of the cabinet between the housing 40 and the drawers are closed by doors 32 hinged at the outer edges to the corner members 11 as shown at 33.

By this means the "pockets" formed by the members 30 and 31 are accessible through 45 the ends of the cabinet.

The "pockets" form convenient depositories for the cartons of window shade material, which may be inserted or removed through the doors 32, and by providing a 50 plurality of the pockets, a corresponding number of different colors or grades of the

material may be supported in convenient and independently accessible position.

The improved cabinet may be constructed of any suitable material or of any suitable 55 size but will preferably be constructed of sheet metal.

The preferred embodiment of the invention is disclosed in the drawings and set forth in the specification, but it will be understood that modifications within the scope of the claims may be made in the construction without departing from the principle of the invention or sacrificing any of its advantages. 65

What is claimed as new is:—

1. A device of the class described including supporting members in spaced relation and mounted for rotation, each of said supporting members having outwardly opening 70 marginal sockets directed tangentially to the axis of the same, and supports bearing at their ends respectively in said sockets and extending between said members and adapted to support articles to be displayed. 75

2. A cabinet of the class described comprising a casing including vertical end members, a plurality of bars in uniformly spaced relation and connected to the vertical end members, the bars having segmental outer faces and coacting to form bearing devices, a disk at each end of the casing and having openings respectively engaging said bearing bars, a plate attached to the inner face of each disk and having marginal seats directed tangentially of the disks, and holding members engaging at their ends in the said seats. 80

3. A device of the class described including supporting members in spaced relation 90 and mounted for rotation, each of said supporting members having sockets extending tangentially thereof with a member closing their outer ends, and supports bearing at their ends respectively in said sockets and 95 extending between the spaced members, and held from longitudinal displacement by the closure members.

In testimony whereof, we affix our signatures hereto.

WILLIAM A. HALL.
OTIS ROBINSON.
